SPOOL HOLDER

Filed Sept. 4, 1931

Ralph H. Carter. Inventor

Thomas & Byron attorney

UNITED STATES PATENT OFFICE

RALPH H. CARTER, OF JOHNSON CITY, TENNESSEE, ASSIGNOR TO AMERICAN GLANZSTOFF CORPORATION, OF NEW YORK, N. Y., A CORPORATION OF DELAWARE

SPOOL HOLDER

Application filed September 4, 1931. Serial No. 561,115.

My present invention relates to the provision of a novel spool holder.

It is an object of my present invention to provide a new spool holder having means to hold a spool in place thereon.

A further object of my invention is to provide simple and efficient means to hold a spool securely on a spool holder by providing the spool holder with radially disposed means whereby the said spool may readily be locked in place.

A still further object of my invention is to provide a spool holder with an upstanding portion having formed therein radially disposed slots in which are fitted securing means held in place by means of a flexible or resilient hosing or tube.

These and other objects of my invention will become more apparent from a perusal of the following description and a study of the annexed drawing in which:

Figure 1 is a sectional view taken along lines 1—1 of Figure 2;

Figure 2 is a sectional view taken along lines 2—2 of Figure 1 the spool being omitted.

Figure 3 is a perspective view of one of my holding means.

Referring now more particularly to the drawing, I have shown a spindle 1 having secured thereto by any suitable means my new holder designated by 2. My new holder comprises a cylindrical base 3 having formed therein a bore 4 adapted to receive the spindle. The upper portion 5 of the base provides a suitable seat 5 for the beaded end of a spool 7.

Located inwardly on the periphery of the base is an upstanding cylindrical member 8, which, as may clearly be seen from Figure 1, is an integral part of the holder. This member is provided with a bore 9 communicating with the bore 4, but of larger diameter, thus providing a seat 10 for the hose or tube 11. This hose, or tube, may be made of any suitable material, as, for example, soft rubber, and fits snugly against the inner wall of the cylindrical member 8.

This member is provided at spaced intervals with integral ribs 12 extending the length thereof and extending outwardly therefrom to a dimension which fits the in-

side of the spool 7. Elongated slots 13 are formed in these ribs and communicate with the bore 9. The top and bottom walls of each slot are inclined inwardly as is clearly shown at 14, Figure 1. Fitting within these slots are correspondingly shaped holding members or blades 15. When the spool is placed on the holder the holding members or blades are forced inwardly and because of the inclination of these slots, these blades are forced not only inwardly but also outwardly from the base 3, thus forcing the top of the blade against the upper inclined surface of the slot. Due to the resiliency of the holding members the pressure thus exerted upon the upper wall of each slot will tend to force the blades downwardly, thus holding the spool firmly against the base 3.

Referring now to Figure 3, I have shown one of the blades or holding means in perspective. As may be readily seen, each blade or holding member comprises an elongated body member 16 having a tapered portion 17 formed on the upper end and an abutment 18 along one of the long sides thereof. The tapered portion functions as a cam surface for a purpose to be hereinafter described, and the function of the abutment means 18 is to prevent the holding members or blades from dropping out of the slots provided therefor. The abutment 18 as may clearly be seen, is wider than the slot.

In the assembly of my holder with the spindle, the holder is secured to the spindle by any suitable means such as by a nut. The tube or hose tends constantly to force the holding members or blades outwardly, the outward movement thereof being limited by the abutments. The spool 7 is then positioned on the holder and its beaded edge, striking the tapered portion of the blades, forces the said blades inwardly against the tube. By virtue of the inclined walls of the slots and the correspondingly shaped portions of the blades, the spool is held firmly against the portion 5 as explained above. Moreover the outer surfaces of the ribs 12 act as means to center the spool on the holder.

From the above description it will be appreciated that my new holder has several

advantages. By using holding members or blades having tapered portions, the spool may be more readily positioned on the holder, since the said tapered portions have a slight

- 5 camming action. By providing the slots with inclined surfaces the blades will function not only to hold the spool on the holder but also to hold the spool against the base 3. The holding members of blades are pressed 10 against the spool by means of the tube or hose, thus causing the necessary friction to hold the spool firmly in place on the spindle.

Moreover the spool is located concentrically around the spindle by means of the 15 projecting ribs and is also located longitudinally with the respect to the spindle by means of the base.

It is to be understood that my invention is not limited to the precise construction shown 20 but that it includes within its purview whatever changes come within the terms or spirit of the appended claims.

What I claim as new is:

1. A holder adapted to receive a spool comprising a base, a cylindrical member, spaced 25 ribs extending outwardly therefrom and having slots formed therein, correspondingly shaped holding blades mounted in said slots, and a resilient tube positioned in said cylindrical members and contacting with the inner edges of said holding blades, whereby the latter are maintained in engagement with a spool.

2. A spool holder comprising a base, having 35 a bore adapted to receive a spindle, a cylindrical member integrally formed therewith and having a bore of greater diameter than the first mentioned bore, a resilient tube positioned in the bore of the said cylindrical member, spaced ribs projecting outwardly 40 from the cylindrical member and each having a slot formed therein, the top and bottom walls being inclined toward the periphery of the base, blades positioned in the said slots, each blade having correspondingly inclined surfaces, an abutment formed on each blade

limiting the outward movement thereof and contacting with said resilient tube, whereby when a spool is placed on the holder the blades are held in contact therewith.

3. A spool holder comprising a base, a hollow cylindrical member integral with said base, a resilient tube fitting within said cylindrical member, spaced ribs formed integral with the said cylindrical member and having inclined slots formed therein, holding blades 75 having correspondingly shaped surfaces located in said slots, whereby when a spool is placed on the holder the holding blades are forced inwardly and upwardly against the resilient tube and upper wall of the slot, and the pressure thus exerted against the holding blades tends to force them downwardly, thus holding the spool firmly against the 80 said base.

4. A spool holder comprising a base, having a bore adapted to receive a spindle, a cylindrical member integrally formed therewith and having a bore of greater diameter than the first mentioned bore, a resilient tube 85 positioned in the bore of the said cylindrical member, spaced ribs projecting outwardly from the cylindrical member and each having a slot formed therein, the top and bottom walls being inclined toward the periphery of the base, blades positioned in the said slots, each blade having correspondingly inclined 90 surfaces, said resilient tube normally pressing said blades outwardly in said slots, and means to limit the outward movement of said blades.

5. A holder adapted to receive a spool comprising a base, a cylindrical member spaced 95 ribs extending outwardly therefrom and having slots formed therein inclined toward the outer periphery of the base, correspondingly shaped holding blades mounted in said slots, and a cylindrical elastic means positioned in 105 said cylindrical member and contacting with the inner edges of said holding blades.

RALPH H. CARTER.
